UNITED STATES PATENT OFFICE.

JOHN P. NIKONOW, OF NEW YORK, N. Y., ASSIGNOR, BY MESNE ASSIGNMENTS, TO THE HAWTHORNE COMPANY, OF BRIDGEPORT, CONNECTICUT, A CORPORATION OF CONNECTICUT.

ELECTRIC LAMP.

1,392,441.

Specification of Letters Patent. Patented Oct. 4, 1921.

Application filed April 9, 1919. Serial No. 288,775.

To all whom it may concern:

Be it known that I, JOHN P. NIKONOW, a citizen of Russia, and a resident of the city, county, and State of New York, have 5 invented a new and useful Improvement in Electric Lamps, of which the following is a specification.

My invention relates to the electric lamps, used generally on the automobiles, motor- 10 boats, etc., which are commonly known as "spotlights", and has a particular reference to such lamps, which can be removed with the reflector from the housing and with the help of extension conductors used as trouble 15 or portable lamps.

My invention is explained more fully on the accompanying drawings, in which—

Figure 1 is a sectional elevation of the assembled lamp and Fig. 2 is a view of the 20 lamp, when it is removed from the housing and used as a trouble lamp.

My lamp consists of a reflector I, the front end of which is covered with a glass plate 2. A rim 3 fastens the glass and reflector 25 together by means of a bead 6 and a ring 4. Screws 5 serve to fasten the ring and ream together. A metal tube 7 is inserted into the opening in the rear end of the reflector and is fastened in its place. The in- 30 side end of the tube receives a lamp 8, and to the other end of this tube is fastened a disk or plate 9. The tube 7 forms a support for the flexible conductors II, which can be wound on this tube, as shown. One end of 35 the conductors is connected to the lamp leads 10, and the other extends through the bushing 12 in the housing 13 and is connected to the source of the electric current.

The front end of the housing I has a screw 40 or pin 14, which fits into a two way groove or slot 15 in the cylindrical extension of the rim 3. This construction allows the reflector with the lamp to be removed from the housing and used as a portable lamp, when- 45 ever desired, or inserted in the housing and used as a searchlight. The screw 14 may be tightened by hand to prevent the lamp from jarring loose. Felt or rubber packing 24 may be cemented to the inside surface of 50 the rim and form a watertight joint.

A mirror 16 may be fastened to the rear end of the housing to enable the driver to see back of the automobile. The housing 13 has lugs 17 with a pin 19, which is con-

nected to the rod 18. This rod is clamped 55 between two plates 20 by means of screw 21. Screw 23 serves to draw together extension 22, with which the whole bracket is fastened to some part of a vehicle.

Springs 25 may be fastened to the rear of 60 the housing. These springs enter the rear end of the tube 7 under some tension, thus keeping the whole portable element (con- 65 sisting of a reflector, lamp, supporting ex- tension and a flexible cord) tight and se- cure from vibration.

Fig. 2 shows a different method of bring- 70 ing conductors through the housing. Here instead of a bushing 12, a connector 26 is employed, to which the ends of lead II are fastened inside of the housing. A flexible lead 27 with the connector 28 is used in this case to establish connection with the source of the current.

Important advantages of my lamp are, 75 that it can be used as a portable lamp with- out removing the housing from the bracket, simply by removing a portable element from inside of this housing, this portable element consisting of an inclosed lamp with a con- 80 venient handle and an extension cord. And when this portable element is inserted in the housing, this lamp has all the features of an ordinary lamp, spotlight or projector.

I claim as my invention:

In a lighting apparatus, the combination 85 of a housing provided with a front opening; a portable unit normally housed within said casing and removable therefrom through said opening, said unit comprising a light- 90 source, a reflector associated therewith, a tube supported by and extending rearwardly from said reflector and supporting said light-source, a disk carried by and adjacent to the rear end of said tube; and light-source 95 supply conducting means extending from said light-source within said tube and laterally therethrough forward of said disk and through said casing to the exterior of the latter, said conducting means being nor- 100 mally wound on said tube forward of said disk.

In testimony whereof I have hereunto sub- 100 scribed my name this 27th day of February, 1919.

JOHN P. NIKONOW.
